UNITED STATES PATENT OFFICE.

GEORGE GOODSR, JR., OF NEW YORK, N. Y., ASSIGNOR TO IDEAL COATED PAPER CO., OF BROOKFIELD, MASSACHUSETTS, A CORPORATION OF NEW JERSEY.

VENEERING-TAPE.

1,038,874.

Specification of Letters Patent. Patented Sept. 17, 1912.

Application filed January 16, 1912. Serial No. 671,429.

To all whom it may concern:

Be it known that I, GEORGE GOODSR, Jr., a citizen of the United States, residing at New York, in the county of New York and 5 State of New York, have invented certain new and useful Improvements in Veneering-Tape; and I do hereby declare the following to be a full, clear, and exact description of the invention, such as will enable 10 others skilled in the art to which it appertains to make and use the same.

This invention relates to veneering and more particularly to the tape used in holding the abutting edges of pieces of veneering together for application.

An object of my invention is to provide a perforated or slotted paper tape as a substitute for cloth or fabric as paper tape has advantages over fabric tape in that it is 20 cheaper, more pliable, more easily torn or severed where desired and more easily applied.

Another object of my invention is to provide a gummed perforated paper tape 25 so that in building up veneering the heated glue applied thereto can pass through the perforations and soften the glue under the tape to prevent the increased thickness of glue.

Further objects will be apparent from the following specification, appended claims and drawings in which:

Figure 1 is a perspective view of the device applied, Fig. 2 is a plan view of one 35 form of tape, Fig. 3 is a modified form, Fig. 4 is a further modified form, Fig. 5 is a further modified form.

In built up veneers, the laminations of veneering are formed of two or more independent pieces which before being applied are secured to each other by veneering tape. The first ply or lamination is applied after the surface to receive it has been covered with glue or an adhesive, then the subsequent laminations are likewise applied after having the surfaces to receive them covered with glue or the like.

The tape used in binding the several pieces of each lamination of veneering remains in its relative position when the veneer is completed with the exception of that applied to the outside lamination, which is removed as by sandpapering the outer surface. To prevent ribs being formed by the 5 tape secured to one lamination in the sub-

sequent lamination, such as by the thickness of the glue under and above said tape, the warm glue applied to each lamination prior to the application of a subsequent lamination of veneering, may be permitted 60 to soften the glue under the tape so that after the subsequent lamination is applied and placed under pressure, the glue under as well as over the tape is spread in a thin film of imperceptible thickness, and the tape 65 itself is pressed into the surface of the adjacent faces of veneer if necessary.

In order that the warm glue may affect the glue under the tape, the tape is perforated and referring to the drawing here- 70 with, there is shown a tape 10 having the perforations or slits 11 formed therein. The pieces of veneering 12 and 13 are brought together and the tape 10 is applied so as to overlap the abutting edges and the 75 seam 14 formed by the meeting edges, and said tape holds the pieces 12 and 13 in relative position to one another until the veneering is applied and the glue or adhesive which holds the same is set, at which time 80 the tape 10 may be removed in the event of the veneering being the outer ply or lamination or if succeeding laminations are to be applied, the pieces of veneering 12 and 13 as well as the tape 10 are covered with a 85 film of warm glue which may pass through the perforations in the tape as above described.

Fig. 2 shows a tape of the preferred form in which the perforations are formed in 90 substantially the entire tape. Figs. 3, 4 and 5 are modified forms of my invention.

I am aware that paper has been used to bind the edges of veneering together temporarily but the idea of perforating or slitting 95 said tape to permit the pressure applied thereto to force the glue thereunder evenly over the surface through said slits or openings is new and novel and

Having thus described my invention, I 100 claim:

1. In combination with the abutting edges of pieces of veneering, a perforated tape overlapping said abutting edges and the seam formed thereby, said tape having 105 a film of glue thereunder to securely hold the abutting edges in place and said tape permitting the passage of heated glue there- through to soften the film of glue under said tape when desired.

2. In combination with the abutting edges of pieces of veneering, a perforated tape overlapping the abutting edges and the seam formed thereby, said tape having one face thereof coated with a film of adhesive which binds said tape to the edges of the veneering, said veneering and tape being capable of receiving similar plies of veneering, and said tape permitting the passage of heated adhesive therethrough when subsequent plies are added thereto, thereby permitting the film of glue under said tape to be softened and spread into an imperceptible film.

15 3. In combination with the abutting edges of pieces of veneering, a perforated

tape having one face thereof supplied with a film of adhesive, said tape being secured to said veneering so as to overlap the abutting edges thereof and the seam formed by the abutting edges, said tape holding said pieces of veneering together, and said tape permitting subsequently applied warm adhesive to pass therethrough to soften the adhesive between the tape and veneering. 20 25

In testimony whereof I affix my signature in presence of two witnesses.

GEORGE GOODSIR, JR.
